J. F. HUGHES

AUTOMOBILE SIGNAL

Filed June 28, 1922

Patented June 5, 1923.

1,457,703

UNITED STATES PATENT OFFICE.

JAMES F. HUGHES, OF BRIDGEPORT, CONNECTICUT.

AUTOMOBILE SIGNAL.

Application filed June 28, 1922. Serial No. 571,447.

To all whom it may concern:

Be it known that I, JAMES F. HUGHES, a citizen of the United States, residing at Bridgeport, in the county of Fairfield and State of Connecticut, have invented a new and useful Improvement in Automobile Signals; and I do hereby declare the following, when taken in connection with the accompanying drawings, and the characters of reference marked thereon, to be a full, clear, and exact description of the same, and which said drawings constitute part of this application, and represent, in—

Fig. 1 a side view of an automobile signal constructed in accordance with my invention.

Fig. 2 an end view of the same.

Fig. 3 a vertical sectional view on an enlarged scale.

Fig. 4 a sectional view on the line 4—4 of Fig. 3.

Fig. 5 a sectional view on the line 5—5 of Fig. 3.

Fig. 6 a side view, partly broken away, of the signal tube, detached.

Fig. 7 a top view of the same.

Fig. 8 a side view, partly broken away, of a lamp-supporting frame.

Fig. 9 a top view of the same.

This invention relates to improvement in automobile signals, the object being to provide a signal which will indicate to a traffic officer whether or not the car is running with the consent of the owner; whether it is supposed to be parked, or whether it is supposed to be in the garage, and the invention consists in the construction as hereinafter described and particularly recited in the claims.

In carrying out my invention, I employ a tubular casing 10 adapted to be secured to an automobile at any desired point where clearly visible. This casing is formed with a longitudinal sight opening 11. The casing is provided with a bottom 12 and closed at its upper end by a plug 13, in which is mounted a pin tumbler lock cylinder 14, the concentric stud 15 of which engages with a bolt 16 adapted to engage with one of three locking recesses 17 in the casing. Preferably, the plug 13 will be formed with a flange 18 extending downward below the bolt 16. Within the casing is a sleeve 19 resting on the bottom 12 and formed on its upper end with notches 20 to receive fingers 21 at the inner end of the plug 13, so that, when the plug is turned, the sleeve 19 will

be turned with it. This sleeve is preferably formed from glass, or other transparent material, and is divided into three faces,—one face, 22, being clear and bears a registration number; another face, 23, is red, and another face, 24, is blue, or any other contrasting color.

It is obvious that if desired the tube 19 may be made up of three segmental members.

Within the tube is a shell 25 supporting electric lamps 26, the wires of which may extend through a perforation 27 in the bottom 12. When the car is being run by the proper party, the signal is turned to expose the registration number through the slot 11, and the tube is locked in this position. When the car is parked, the driver unlocks the plug and turns the plug so as to expose the blue face through the slot 11, and locks the tube in this position. This indicates to any traffic officer that the car is supposed to be parked, and not running with the owner's consent; or, in case the car has been placed in a garage, the tube is turned to expose its red face, thus indicating at once that the car is supposed to be in the garage.

Thus, at a glance, a traffic officer can determine whether a car is being run with the consent of the owner; whether it is a car that is supposed to be parked, or whether it is a car that is supposed to be in the garage, and this is accomplished in a simple manner by means readily operated, but difficult of felonious manipulation.

I claim:

1. An automobile signal comprising a tubular casing formed with a sight-opening, a tube within said casing, and having differential faces, a plug mounted in the top of the casing and interlocked with said tube, and means for locking the plug with said casing.

2. An automobile signal comprising a tubular casing formed with a sight-opening, a tube within said casing and formed with a plurality of differential faces, a plug closing the upper end of the casing and interlocked with said tube, key-operated means mounted in said plug and adapted to lock the plug against rotation in the casing, and electric lights mounted within said tube.

3. An automobile signal comprising a tubular casting open at one end, closed at the opposite end and formed with a sight-opening, a tube mounted in said casing for rotation therein and provided with differential

faces, a plug adapted to enter the open end of the casing and engage with said tube for rotating the same, key-operated means mounted in said plug, and including a bolt 5 adapted to interlock the plug with the casing, the said plug formed with a flange extending over the outer end of the casing to a point below said locking-bolt.

In testimony whereof, I have signed this specification in the presence of two subscribing witnesses. 10

JAMES F. HUGHES.

Witnesses:
